(57) **CLAIM**

The ornamental design for a spring power contact having non-linear slot, as shown and described.

DESCRIPTION

FIG. 1 is a front/top perspective view of a spring power contact having non-linear slot in accordance with the present invention;

FIG. 2 is a front elevation view thereof;

FIG. 3 is a right elevation view thereof;

FIG. 4 is a rear elevation view thereof;

FIG. 5 is a left elevation view thereof;

FIG. 6 is a top plan view thereof; and,

FIG. 7 is a bottom plan view thereof.
